Primary Examiner — Janice Hallmark(74) *Attorney, Agent, or Firm* — McGarry Bair PC**(57) CLAIM**

The ornamental design for a ceiling fan motor housing, as shown and described.

DESCRIPTION

FIG. 1 is a top perspective view of a ceiling fan motor housing;

FIG. 2 is a bottom perspective view of the motor housing of FIG. 1;

FIG. 3 is a top view of the motor housing of FIG. 1;
 FIG. 4 is a bottom view of the motor housing of FIG. 1; and,
 FIG. 5 is a front side view of the motor housing of FIG. 1,
 with rear, right, and left side views being identical thereto.
 Portions of the ceiling fan motor housing and the ceiling fan
 environment shown in broken lines form no part of the
 claimed design.
